UNITED STATES PATENT OFFICE

SIEGFRIED GROSS, OF ESSEN, GERMANY, ASSIGNOR TO FRIED. KRUPP AKTIENGESELLSCHAFT, OF ESSEN-ON-THE-RUHR, GERMANY

LAMINATED SPRING

Application filed August 3, 1928, Serial No. 297,210, and in Germany October 27, 1927.

The invention relates to laminated springs, more particularly to springs intended for vehicles and consists primarily in making the individual spring elements of equal length, as well-known, but in designing them at least approximately as bodies of uniform strength with varying thickness, so that they do not touch each other upon the spring system being loaded.

In order that the invention may be more easily understood, an embodiment of the subject-matter of the same is illustrated by way of example in the drawings which accompany and form part of this specification. In the drawings.

Figure 1 is an elevation of the first embodiment,

Figure 2 is the corresponding top view,

Figure 3 is a section on line 3—3 of Figure 2 on an enlarged scale,

Figure 4 is a detail of Figure 3, seen from the left.

Referring now to Figures 1-4, all of the spring elements D, D¹ are of equal length and uniform width, while their thickness decreases from the band C towards their free ends approximately according to a common parabola. The uppermost and lowermost elements D of the system have eyes on each end that embrace pins e¹ of heads E, see Figure 3. The free ends of the remaining spring elements D¹ engage with play recesses e² provided in the heads E. Pins e³, Figure 3, of heads E serve to connect the latter with the rig-

ging.

Upon the described spring system being loaded, the heads E shift parallel to the band C. When this takes place, sliding friction arises only between the eyes d² of the spring elements D and pins e¹, while the elements D¹ roll on the rounded-off edges of the recesses e². Consequently the system exerts a spring action even with slight shocks, this being impossible with the known laminated springs, due to the internal friction existing between the individual spring elements. Besides this, compared to an ordinary spring of the same length, same number of elements, same thickness of the latter in the midst, and with the same load as one of the known spring sys-

tems, the described spring system possesses a deflection which is by one third greater than that of the former, so that it is capable to take up a correspondingly increased amount of deformation.

What I claim and desire to secure by Letters Patent, is:—

1. In a spring system individual spring plates of equal length, and diverging thickness from their centers, said spring plates contacting at their centers, means rigidly uniting said plates, and head pieces rotatably engaging the ends of at least two of said plates and having supports for the ends of the other spring plates.

2. In a spring system individual spring plates of equal length and diverging thickness from their centers, said spring plates contacting at their centers, means rigidly uniting and distancing said plates, and head pieces rotatably engaging the ends of at least two of said plates and having rounded faces loosely supporting the ends of the other spring plates.

3. In a spring system a stack of individual spring plates of equal length and diverging thickness from their centers, said spring plates contacting at their centers, mounting means rigidly connecting and distancing said spring plates, and mounting supports rotatably engaging the ends of two of said plates and having recesses with rounded edges abutting with the ends of the other plates.

The foregoing specification signed at Cologne, Germany, this 20th day of July, 1928.

SIEGFRIED GROSS.
